UNITED STATES PATENT OFFICE.

JOHN H. MACALMAN, OF SOMERVILLE, MASSACHUSETTS.

DESIGN FOR A VEHICLE-BODY.

SPECIFICATION forming part of Design No. 35,911, dated May 13, 1902.

Application filed February 12, 1902. Serial No. 93,805. Term of patent 7 years.

To all whom it may concern:

Be it known that I, JOHN H. MACALMAN, a citizen of the United States, residing at Somerville, in the county of Middlesex and State 5 of Massachusetts, have invented and produced a new and original Design for a Vehicle-Body, of which the following description, in connection with the accompanying drawing, is a specification, like letters on the drawing 10 representing like parts.

The drawing in side elevation illustrates my new design.

As shown in the drawing, the leading and material feature of my design consists of a 15 dasher-box shaped, as shown, to present substantially vertical front and rear lines a b . The vertical front line a at its lower end sweeps rearwardly and downwardly in an elliptical convex curve a' to meet the bottom 20 line a^2 of the body. The rear vertical line b terminates at its bottom in a similar curve or sweep blending into and meeting the top

line of the rear portion of the body at b' . At the top of the box the front and rear vertical lines are connected by a forwardly and upwardly inclined slightly-concave top line c , which meets the front line in a relatively sharp apex c' and the rear line in a convex curve or sweep c^2 .

The rear of the body carrying the dasher- 30 box described is shown in dotted lines.

Having described my invention, what I claim, and desire to secure by Letters Patent, is—

The design for vehicle-body herein shown 35 and described.

In testimony whereof I have signed my name to this specification in the presence of two subscribing witnesses.

JOHN H. MACALMAN.

Witnesses:
